US0D1080140S

(12) **United States Design Patent** (10) **Patent No.:** **US D1,080,140 S**
(45) **Date of Patent:** **** Jun. 24, 2025**

(54) **WEARABLE BLANKET**

(71) Applicant: **Kai Zhong**, Jiande (CN)

(72) Inventor: **Kai Zhong**, Jiande (CN)

(**) Term: **15 Years**

(21) Appl. No.: **29/985,039**

(22) Filed: **Jan. 15, 2025**

(51) **LOC (15) Cl.** **02-02**

(52) **U.S. Cl.**

USPC **D2/719**; D2/828

(57) **CLAIM**

The ornamental design for a wearable blanket, as shown and described.

DESCRIPTION

FIG. 1 is a front perspective view of a wearable blanket, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of the wearable blanket thereof with the pocket feature in an open configuration; and,

FIG. 10 is a top view of the wearable blanket with the pocket feature in an open configuration.

The broken lines in the drawings illustrate the portions of the wearable blanket, which form no part of the claimed design.

1 Claim, 10 Drawing Sheets
